UNITED STATES PATENT OFFICE.

WESLEY WILLNER KÜHLMANN, OF WOODCLIFFE-ON-HUDSON, NEW JERSEY.

DINING-TABLE PLATE-HEATING APPLIANCE.

1,230,727.

Specification of Letters Patent. Patented June 19, 1917.

Application filed March 9, 1917. Serial No. 183,665.

To all whom it may concern:

Be it known that I, WESLEY W. KÜHLMANN, a citizen of the United States, and a resident of Woodcliff-on-Hudson, in the county of Hudson and State of New Jersey, have invented a new and Improved Dining-Table Plate-Heating Appliance, of which the following is a full, clear, and exact description.

10 This invention relates to a plate-warming appliance adapted to be used on a dining table or the like for the purpose of keeping the plate warm while the diner is eating from the plate.

15 The invention has for its general objects to provide an appliance of this character which is of comparatively simple and inexpensive construction, reliable and efficient in use, and so designed that it is of neat and attractive appearance.

20 A more specific object of the invention is the provision of a plate-warming device which comprises a distributor adapted to be connected with an electric lamp socket to receive current from a service circuit, and the distributor embodies a plurality of plugs which are connected by cords to the several heating disks on which the dining plates are intended to rest to keep viands 25 on the plates warm during the meal.

25 Another specific object of the invention is the provision of a novel heating element especially adapted for heating plates and which is protected on the under side so as to prevent marring of the finish of the dining table, and furthermore, the heater is comparatively thin so as not to raise the dining plate too high from the table.

30 With such objects in view, and others which will appear as the description proceeds, the invention comprises various novel features of construction and arrangement of parts which will be set forth with particularity in the following description and 35 claims appended hereto.

35 In the accompanying drawings, which illustrate certain embodiments of the invention and wherein similar characters of reference indicate corresponding parts in all 40 the views,

45 Figure 1 is a plan view of the distributor with the top plate removed and a portion in section, and also showing one of the heaters connected with the distributor and in horizontal section on the line 1—1, Fig. 4;

Fig. 2 is a central vertical section of the distributor, on the line 2—2, Fig. 1;

Fig. 3 is an enlarged sectional view of the heater on the line 3—3, Fig. 1;

Fig. 4 is a detail sectional view on the line 4—4, Fig. 1.

Referring to the drawing, A designates the distributor and B one of the plate-heating devices. The distributor comprises a suitably shaped structure which is adapted to be placed at the center of the dining room table, and it may be finished or ornamented in a variety of ways. A cord conductor 1 leads from a lamp socket in a chandelier or the like and supplies current to various heating devices B through the distributor. The distributor A comprises a flat body 2 of insulating material and a top plate 3, the plates being so formed as to provide a chamber 4 or a juncture box. In the chamber 4 are conductors 5 and 6 that are connected respectively by binding posts 7 and 8 with the wires of the conducting cord 1. The conductors 6 and 7 have branches 9 and 10 respectively which are radially disposed and each pair of branches 9 and 10 connects with socket or jaw members 11 and 12 which project outwardly through the wall of the chamber 4. A removable plug 13 has a pair of tongue contacts 14 and 15 which are 25 plugged into the jaw or socket members 11 and 12, respectively, and these plugs 13 are connected by conducting cords 16 with the heating devices B. In the present instance the distributor is shown with six plugs so as to be suitable for a dining table set for six persons, but it is not essential to have all the plugs attached if fewer persons are dining.

Each plate-warming device B comprises an aluminum or other metal shell 17 of good heat-conducting quality which is open at its bottom, and in this open bottom is a disk or plate of cork 18 or equivalent material which is fastened by the edge of the shell being turned back into a flange 19, as shown 25 in Fig. 3. In the shell is a body of asbestos or equivalent insulating material 20 shaped to provide a chamber 21 in which is disposed the heating element. This heating element comprises a central disk 22 of mica or equivalent material which forms a carrier on which is wound a heating coil 23. On opposite sides of the heating element are sheets of mica 24 and 25 to insure proper insulation. The heating wire is wound helically 105 110

on the disk or sheet 22, beginning at 26, and the return end 27 is insulated from the convolutions of the winding by a strip of mica 28. The ends of the heating winding are connected with binding posts 29 and 30 arranged in a binding post block 31 anchored in the body of the heating device, as clearly shown in Fig. 1. The binding posts 29 and 30 are connected with the wires of the cord conductor 16. The current flowing through the winding 23 produces a high degree of heat which is conducted to the metal plate or shell 17 on which the dining plate bears to be heated by direct contact and by radiation. If the dining plate is heated to the desired temperature the heating device on which the dining plate rests can be uncoupled from the distributor by pulling out the plug 13. When the plate warming device is not required the supply of current is cut off at the lamp socket chandelier.

From the foregoing description taken in connection with the accompanying drawing, the advantages of the construction and method of operation will be readily understood by those skilled in the art to which the invention appertains, and while I have described the principle of operation, to-

gether with the device which I now consider to be the best embodiment thereof, I 30 desire to have it understood that the device shown is merely illustrative and that such changes may be made when desired as fall within the scope of the appended claims.

Having thus described my invention, I 35 claim as new and desire to secure by Letters Patent:

1. An electric plate-warming device comprising a disk-like body formed of a top metal plate, a body of insulation under the 40 plate, a heating conductor in heating relation to the plate, and a sheet of cork forming an insulating cushion for the bottom of the body.

2. A plate-heating device comprising a 45 shell, a body of insulating material disposed therein, a sheet of material disposed under the body and fastened to the shell and forming an insulator and cushion, a sheet of mica disposed between the body and top of 50 the shell, a winding of wire on the sheet of mica, sheets of mica above and below the winding, and means for connecting the winding with a supply circuit.

WESLEY WILLNER KUHLMANN.
